RIBBON POSITIONING MEANS FOR
WRITING MACHINES

Adolph F. von Soden, Los Angeles, Calif.

Application August 13, 1943, Serial No. 498,447

2 Claims. (Cl. 197—156)

1

My invention relates to typewriters or like machines in which one object is to provide a device in said typing machines adapted for controlling the position of the typewriter ribbon and more particularly to such construction thereof, whereby the position of a ribbon may be shifted and so held in any special position when the printing character type bars strike upon the ribbon surface during the operation of said machine.

Another object of my invention is to provide a suitable detachable ribbon shifting device which when attached to the typing machine it will become substantially a part thereof, and when in operation, to be adapted for holding, controlling and for maintaining said ribbon in its place and position, such as the top edge section, the middle section or the bottom edge section thereof, and thereby increasing considerably the life and the usefulness of said ribbon and for preventing its edge-wise stretching.

Further object of my invention is to provide said detachable device, or an article of manufacture, which is attachable to or made an integral part of a machine herein described, and which is made in such a form or construction so as to be adapted for the purpose of controlling any position of the printing ribbon, and which, in addition, may be adapted to be used in and for any make, style or design of a typewriter machine, adding machine, teletype machine, billing, adding or calculating machine or the like, and be applicable to and for any device, machine or apparatus where a typing ribbon or the like is employed and used for printing the type characters upon the paper surface or the like.

Other and further objects and advantages of my invention as will hereinafter more fully appear, I attain by the construction herein shown on the drawings and described in the specification forming a part of my application.

Reference is had to the accompanying drawings, in which the similar reference characters denote the similar parts.

In the drawings:

Fig. 1 is the diagrammatical elevational view of the moving parts of a typewriter machine, showing same in relation to the striking type bar movement and the ribbon vibrator guiding means, also the ribbon adjusting and controlling means.

Fig. 2 is the fragmentary top view of the ribbon controlling means, disclosed as my invention.

Fig. 3 is the front elevational view of the ribbon holding and controlling device, which is adapted for attaching same to the ribbon guiding

2

member of the typewriter machine, showing it in a modified form, and showing same in its various positions at which the ribbon may be held during the operation of the typing machine.

Fig. 4 is the side elevational view of the ribbon holding and controlling device, taken from the right of the Fig. 3.

Fig. 5 shows the top plan view of the device, taken from the top of the Fig. 3.

Fig. 6 is the vertical sectional view of the device taken on the line 6—6 of the Fig. 5, slightly enlarged.

Fig. 7 shows a fragmentary elevational view of the device, showing its parts more in detail.

15 Describing my invention more in detail, said invention comprises a ribbon control means, generally designated by numeral 2 which consists of a suitable coupling member 4 secured upon a shaft member 6 by means of a set screw 8, said coupling member 4 is provided with a suitable stop 10 which is adapted for engaging a lug member 12, see Fig. 2, and which is an integral part of the cross lever member 14.

10 The end 16 of said cross lever member 14 is provided with a suitable hub member 18 which is pivotally mounted upon said shaft member 6, while the end 20 of said cross member 14 is provided with a suitable fork 22 which is adapted for engaging a cross pin member 24 and which 20 is substantially a part of the ribbon guide member 26.

25 Said guide member 26 holds the ribbon in place and it is supporting it in its position when the character type bars 28 strike the ribbon surface 35 during the printing operation, and by pressing downwardly the key lever 30, which is for pulling down the connecting link 32, thus actuating the forked bar member 34, as shown in Fig. 1.

30 The ribbon movement and its position is controlled by the action of said bar 28 which is pivoted upon a cross shaft 36 and is provided with an extension 38 for engaging the forked end section 40 of the bar member 34.

35 Said bar member 34 is also pivoted upon the 45 upwardly extending end 44 of said connecting link member 32, having the outer end 46 mounted upon a pin 48, the position of which is fixed, for holding said lever member 50 in a fixed position, while the rod member 54 is pivoted upon the 50 upper part and an extension of said lever member 50, which extends therefrom upwardly, as shown.

40 Said pivotal rod member 54, so mounted, has its extended end protruding through an aperture disposed in a lever plate member 58, and also hav-

ing a suitable regulating spring 56 positioned between said plate 58 and the pivotal end of said rod member 54, so that in operation, said spring 56 will rest against said lever plate member 58.

Said lever plate member 58 is rigidly mounted on and connected to said coupling member 4, thus actuating said shaft member 6 and comparatively causing said cross lever member 14, including said ribbon guide member 26 to actuate simultaneously.

The normal, downward position of said lever 14 and the rearward position of said plate member 58 for bearing against the spring 56 is maintained by the weight of said guide member 26 coupled with the weight imposed thereon by the extended end 20 of said lever 14, or, if so desired, a suitable tension spring may be provided therein for accomplishing the results required, which will hold said plate member 58 against said spring 56, as shown.

In order to control the position of said ribbon and to hold it in any selected location while same is guided by said vibrator guide member 26, that is, to hold it at the top edge section, the middle section or the bottom section edge, as shown generally at "G," "B," and "A" respectively, see Fig. 3 (without the attachment), said shaft member 6 is provided with a suitable collar 60 which is secured thereon by means of a key, set screw or a pin 62; also, said collar 60 is provided with an extension lever 64 to which a suitable cross bar 66 is attached, at the bar end 68, having its other end 70 pivotally connected to an extending lever 72 which is substantially a member of the bell crank 74.

Said bell crank member 74 is pivotally mounted upon a pivot pin 76 which is a part of a bracket 78, while the other lever 80 of said bell crank 74 is provided with a suitable knob 82, said lever 80 is adapted for engaging a set of selectors 84 which may be slots or the like and thereby holding and maintaining any of the three positions of said ribbon, while the machine is in operation.

In order to set said vibrator guide member 26 to any desired position, said knob 82 with its lever 80 is set within the selector 84, thus selecting any of the A, B or G positions, which actuates the bar 66 and the lever 64, and which causes the collar member 60 and said shaft 6 to turn in the desired direction, which movement controls the position of the coupling member 4, thereby setting said stop 10, so that, when said lever 14 is actuated by the action of the bars 28 then said lug member 12 will stop against said stop 10, while said rod member 54 will move forward and compressing said spring 56, however, preventing said vibrator 26 from actuating the position of said ribbon excepting as permitted by said selector lever 80, and during the operation of said type bars 28.

In the Figs. 3, 4, 5, 6 and 7 is shown an attachable ribbon holder and a guide 86, in a modified form, comprising a base member 88 having a cut out center section 90 which is adapted for clearing the passage of the character hammer members 28, also, having a boss member 92 at each end, each of which is adapted for holding slidably therein a suitable rod member 94, see Fig. 6, which provides an extension 96 and 98, and having at each of its extended ends a suitable spring member 100 and 102 respectively.

Said spring member 100 and 102 are of different lengths, as shown, for holding and for maintaining the position of said ribbon in a floating working position and in a proper relation to said guide 26, and in this manner permitting said

ribbon holder 86 to keep the ribbon in its central position when said lever or selector 80 is placed in its neutral position, thereby permitting said type bars 28 to strike upon the middle section of said passing ribbon.

The spring member 100 is maintained in its place by means of a pin 104 while said spring 102 is held in place by means of a boss member 106 thus forming an extension 108 at the end of said rod member 94.

Said extension 108 extends high enough for engaging the surface rim of the slot 110 in said ribbon guide member 26, then in order to hold said ribbon holder 86 in its place, a suitable back brace member 112 is provided which is riveted in place as at 114 to said boss member 106, thus providing a clamping end 116 while the bottom section 118 of said brace member 112 is provided with a suitably grooved end 120 adapted for straddling said guide member 26 at the inner section of and at the bottom of said slot 110.

In close proximity to said cut out section 90 of said base member 88 a pair of ribbon guiding members 124 are positioned, each of which is provided with a ribbon slot 126 and also a suitable slot passage 128 through which a ribbon may be slipped into said slot 126 without removing same from the spool.

It may now be noted that in operation said ribbon guide 26, which is the standard equipment, raises said ribbon upwardly with each and every motion of the character hammer 28. The standard method of operation being to adjust the ribbon selector for exposing the ribbon surface, that is the top or the bottom edge thereof, to the action of said character hammers. When, however, the neutral position of said selector 84 is employed, then the ribbon holder 86 attached to said guide 26 will assume an adjusted position, causing said holder 86, which is supported in position upon said rod members 94 by the lower springs 100 and the upper springs 102, to hold said ribbon in a central position, and by causing said upper springs 102 to become slightly compressed, which is due to the pressure imposed upon the rod extensions 96 resting upon the typewriter machine.

In this position said guiding members 124 are caused to raise slightly above the normal position, thereby allowing said ribbon disposed therein and held thereby to be used for printing at the ribbon center area, heretofore not subjected to use.

In this manner the unused central section of said ribbon is used, therefore increasing the life and usefulness of a ribbon, and in addition preventing the ribbon edges from wrinkling, which is due to its unevenness caused by the constant hammering by the character hammers 28, upon its edges.

While I have thus described my invention with great particularity, it will be clear that the same may be modified throughout a wide range.

I accordingly do not propose to be limited to the exact details of construction herein shown on the drawings and described in the specification, but reserve the rights in practice to make the necessary changes and modifications therein which may come within the scope of the appended claims.

I claim as my invention:

1. In a vibrator attachment of the class described adapted to be used for guiding a typing ribbon past a printing point, comprising a ribbon guide means, a base in said guide means, a cut

out section in said base, a pair of boss member means disposed at each side of said base, a slide-
able rod means disposed in each of said boss mem-
ber means and extending outwardly therefrom,
a spring means at each end of said rod means,
a spring holding means at each end of said rod
means for holding said spring means in position,
an extension at each upper end of said rod means
having a boss member, and back brace means at-
tached to said boss member of said rod means
for holding said ribbon holding guide means in
position, on the vibrator.

2. In a vibrator attachment of the class de-
scribed, comprising, a ribbon guide means, means
for holding said ribbon guide upon said vibrator,
a set of springs in said last mentioned means for
holding said ribbon guide in a floating position
and for allowing the ribbon to feed therethrough,
so that the upper springs will move said ribbon
guide into its normal floating position.

ADOLPH F. VON SODEN.
